UNITED STATES PATENT OFFICE

158,157

EXTENSIBLE BRACELET

Joseph J. Vastano, East Providence, R. I., assignor
to Flex-Let Corporation, a corporation of Rhode
Island

Application June 18, 1947, Serial No. 139,797

Term of patent 14 years

(Cl. D45—4)

To all whom it may concern:

Be it known, that I, Joseph J. Vastano, a citizen of the United States, residing at East Providence, in the county of Providence, State of Rhode Island, have invented a new, original, and ornamental Design for an Extensible Bracelet, of which the following is a specification, reference being had to the accompanying drawing, forming a part thereof.

Fig. 1 is a top plan view of an extensible bracelet showing my new design;

Fig. 2 is a fragmentary bottom plan view of one end of the bracelet;

Fig. 3 is a fragmentary edge elevational view of one end of the bracelet;

Fig. 4 is a fragmentary top plan view of one end of the bracelet with the links in an extended position;

Fig. 5 is a fragmentary top perspective view of one end of the bracelet; and

Fig. 6 is an exploded side elevational view of a top and bottom link.

The characteristic feature of my design for ex-

tensible bracelet of the type having generally S-shaped top links, as shown, resides in the particular surface contour of said top links, each being convexly curved longitudinally thereof and straight transversely thereof and each having straight ends located at the opposite side margins of the bracelet.

I claim:

The ornamental design for an extensible bracelet, as shown and described.

JOSEPH J. VASTANO.
